UNITED STATES PATENT OFFICE.

AQUASIE E. WEITKAMP, OF NEW YORK, N. Y.

CONTAINER.

Application filed February 12, 1921, Serial No. 444,368. Renewed May 20, 1924.

To all whom it may concern:

Be it known that I, AQUASIE E. WEITKAMP, a citizen of the United States, and a resident of the city, county, and State of New York, have invented an Improvement in Containers, of which the following is a specification.

My present invention relates to bottles or other vessels or receptacles for dispensing liquids or other fluids, preferably in measured quantities or units. My present invention aims to provide devices of the character specified which shall be simple and economical to manufacture, and convenient and efficient in operation.

A further object of my invention is to provide devices of the character specified in such forms that the bottles or other vessels or receptacles cannot ordinarily be refilled, but require the use of special and technical equipment for their refilling, such as only a licensed or authorized filler of the bottles or other vessels or receptacles may be expected to possess.

By way of illustration, I shall, in the accompanying specification, describe several illustrative embodiments of the device of my invention, it being, however, clearly understood that my invention is not limited to such illustrative embodiments which are herein described for purposes of illustration only.

Referring to the accompanying drawings, in which I have illustrated several illustrative embodiments of the device of my invention,

Figure 1 is a longitudinal section of one illustrative embodiment of my invention;

Figure 2 is a similar view, partly broken away, of the device of Figure 1 with the filling apparatus installed and in operation; and

Figure 3 is a view similar to Figure 1 of a slightly modified embodiment of the invention.

Referring now more particularly to the device shown in Figures 1 and 2 of the drawing, 10 represents the bottle or other vessel as a whole. The bottle 10 preferably comprises an outer or dispensing compartment 11 and an inner or containing compartment 12. The outer or dispensing compartment 11 communicates by means of a tube 13 with the mouth 14 of the bottle 10.

Communication between the outer compartment 11 and the inner compartment 12

is by means of any suitable device which normally serves to prevent access of liquid from said outer or dispensing compartment into said inner or containing compartment. Said communication should also be of such a character as to permit the flow from the containing compartment 12 into the dispensing compartment 11 of only a measured or predetermined quantity or unit of liquid or other fluid. For this purpose I provide the lower end of the containing compartment 12 with a seal 15, preferably in the form of a reflex seal, having a connection 16 with the bottom of the containing compartment 12, said connection 16 in turn communicating with one branch 17 of the reflex seal 15, there being a connection 18 for bringing the branch 17 into communication with the remaining branch 19 of the seal 15. Preferably, the branches 17 and 19 are transverse to the length of the bottle so as to be substantially horizontal when the bottle is upright. In this way the opening 20 of the seal 15 is near the inner face of the outer compartment 11 and is horizontally positioned.

The bottle comprising the illustrative embodiment of my invention shown in Figures 1 and 2 of the drawing may be utilized in substantially the following manner: There is inserted in the mouth 14 of the bottle a cork or other stopper 21 through which passes a pipe 22 having a cock or other valve 23 controlling communication of the tube 22 with any suitable evacuating means, such as an exhaust pump. Also passing through the cork or other stopper 21, and like the tube 22 communicating with the interior of the bottle 10, is a tube 24 provided with a cork or other valve 25 and leading to the source of supply of the liquid or other fluid with which the bottle 10 is to be filled. In the filling operation the cock 23 is first turned so as to bring the evacuating device into operative connection with the interior of the bottle 10, the cock 25 being closed. The evacuating device is now maintained in operation until the bottle 10 has been evacuated, whereupon the cock 23 is closed and the cock 25 is opened. By reason of the vacuum now existing in the bottle 10 in both the dispensing compartment 11 and the containing compartment 12, liquid rapidly fills all parts of the bottle 10, including both the dispensing and containing compartments, up to the desired point,

as to the line 26 shown in Figure 1 of the drawing. The cock 25 is now closed and the bottle sealed in any desired or usual way.

In dispensing the contents of a bottle 5 filled as above, it will be noted that on inverting the bottle the contents of the dispensing compartment 11 will be emptied through the tube 13 and the mouth 14 of the bottle, but very little or none of the 10 liquid in the containing compartment will be removed during this first dispensing operation. On restoring the bottle to its normal position a quantity of liquid flows out of the containing compartment 12 15 through the seal 15 until the opening 20 in the seal is covered up by the liquid in the dispensing compartment 11, whereupon the opening 20 will be sealed against the further flow of liquid from the containing compartment 12 into the dispensing compartment 11. The dispensing operation is now repeated by inverting the bottle 10, only 20 a measured or unit quantity of liquid flowing out of the dispensing compartment 11, 25 which quantity of liquid is replaced by flow from the containing compartment into the dispensing compartment on restoring the bottle to its normal or upright position.

The modification of the device shown in 30 Figure 3 of the drawing is substantially similar to the device shown in Figures 1 and 2, except that the bottle 10' has no tube but instead a passageway 13' communicating with the dispensing chamber 11' by means 35 of a seal 15' which connects the dispensing chamber 11' with the containing chamber 12'. In this case the seal 15' is made up of a whole series of branches 17' and 19' which are successively connected by the 40 bends 18', the seal having an opening 20'. The manner of filling this type of bottle and the operation of it are substantially the same as for the bottle already described, and need not be further elaborated here.

45 It is, of course, to be understood that my invention is not limited to the particular embodiments thereof herein shown and described for purposes of illustration only.

What I claim is:

50 1. A vessel for dispensing units of fluid comprising a dispensing compartment, a containing compartment, and a communication between said dispensing and containing compartments serving normally to prevent 55 access of liquid from said dispensing compartment into said containing compartment, said communication being adapted to permit

the flow of a measured quantity of fluid from said containing compartment into said dispensing compartment for dispensing 60 through said dispensing compartment.

2. A bottle for dispensing units of liquid comprising, in combination, a dispensing compartment, a containing compartment, and a communication in the form of a reflex seal between said dispensing and containing compartments, said communication serving normally to prevent access of liquid from said dispensing compartment into said containing compartment and to permit the 65 flow of a measured quantity of liquid from said containing compartment into said dispensing compartment for dispensing 70 through said dispensing compartment.

3. A bottle for dispensing units of liquid 75 comprising an outer dispensing compartment, an inner containing compartment, and a communication in the form of a reflex seal between said dispensing and containing compartments serving normally to prevent 80 access of liquid from said dispensing compartment into said containing compartment.

4. A non-refillable bottle for dispensing units of liquid comprising, in combination, 85 an outer dispensing compartment, an inner containing compartment, and a communication between said dispensing and containing compartments serving normally to prevent 90 access of liquid from said dispensing compartment into said containing compartment and to permit the flow of a measured quantity of liquid from said containing compartment into said dispensing compartment for dispensing 95 through said dispensing compartment.

5. A non-refillable bottle for dispensing units of liquid comprising, in combination, 100 an outer dispensing compartment, an inner containing compartment, and a communication in the form of a reflex seal between 105 said dispensing and containing compartments serving normally to prevent access of liquid from said dispensing compartment into said containing compartment and to permit the flow of a measured quantity of liquid from said containing compartment into said dispensing compartment for dispensing through said dispensing compartment.

In testimony whereof, I have signed my 110 name to this specification this 7th day of February, 1921.

AQUASIE E. WEITKAMP.
